METHOD AND APPARATUS FOR REFORMING WORN MINING CHAIN LUGS

Application filed February 26, 1931. Serial No. 518,448.

My invention relates to a new and improved method and apparatus for reforming worn mining chain lugs and like devices, which in use have the eyes that receive the chain link bosses subjected to wear and stresses which deform such eyes and render the lug or device thereafter unusable.

My invention has its most important field in the coal mining industry where power driven chains carrying lugs in which cutters are mounted are utilized to undercut the coal and to otherwise serve in connection with mining operations.

I have found by long experience with such mining chains that after relatively short usage due to the severe duties imposed by the work, the mine chain lugs have their eyes subjected to such wear and stresses that these eyes become worn and deformed and as a result the coaction of the sprockets with these lugs is interfered with and excessive wear results, and if this is permitted to continue the sprocket teeth or the chain will break. Therefore, the practice in the industry is that when substantial wear appears in these chain lugs the chain is discarded.

The purpose and object of my invention is to recover the value in these used chains and to reform the chain lugs by a simple and comparatively inexpensive operation which renders them practically as good as new and thus restores full value to the mining chain when reassembled with such reformed lugs.

My invention contemplates removing the worn chain lugs from the mining chain, heating their eyes to a cherry red, and placing them in a press and mounting in the lug eyes mandrels slightly tapered and of such diameter as to render the eye reformed about them slightly smaller than the original eye. Power is then applied to the press and the metal is upset against these mandrels, after which the lug is removed from the press, the taper mandrels are knocked out and the slightly tapered holes are reamed to a true diameter corresponding to that of the original new chain lug. Thus I obtain a reformed or reconditioned lug which is substantially as strong and mechanically as accurate as the original lug and this process can continue

until the gradual loss of metal through the reaming operation and wear will render the eyes too weak for service.

To enable my improved reforming process to be carried into effect, I have shown the preferred mechanism to this end which is illustrated in the accompanying drawings which form a part of this specification, and in which:

Fig. 1 is a side elevation of the press showing a chain lug in position at the completion of the reforming operation with the mandrels shown in cross section;

Fig. 2 is a vertical cross-sectional view taken on the line II—II of Fig. 1;

Fig. 3 is an enlarged side elevation of a worn chain lug showing the mandrels in position and illustrating the extent of the wear and deformation which is to be corrected by the reforming operation.

In the practice of my invention, I have shown the same as especially applied to the reformation of chain lugs which comprise a body portion 5 having end eyes 6 which receive the bosses on the mine chain links. The body of the lug 5 is provided with a suitable aperture such as is formally illustrated at 7, to receive a mining tool (not shown) which is held in place by a set screw adapted to be received in the threaded aperture 8. It will be understood that the body of the chain lug will vary widely according to different designs and uses, and my invention is not therefore concerned with the body structure of the lug but only with the reformation of its eyes 6.

Fig. 3 illustrates the result of wear and strain upon these eyes and shows eyes 6a which are worn and deformed. When eyes get in this condition the chain becomes unserviceable and heretofore has been discarded. In recovering such a chain the lugs are removed, they are heated and while hot, the lug is set between the lower jaw 10 and the upper jaw 11 of a press and the mandrels are inserted in the eyes 6a. These jaws are separated at their outer end in order to permit the extension 12 of the body portion, which carries the cutting tool, to be received therein with ample clearance so as to be unaffected

by the operation of the press. The press jaws are recessed at 13 to receive the rounded ends of the lugs in which the eyes are formed and these recesses are semi-circular in shape and 5 conform to the correct diameters of the reformed eye. The jaws are formed with back walls 14 and 15 which engage and brace the wall 16 of the lug body and thus hold it against deformation or strains during the 10 reforming operation. The press jaw 10 carries a pair of vertical pins 26 which telescope with a loose sliding fit into holes 17 formed in the upper press jaw and a coil spring 18, housed in suitable recesses in the 15 jaws, will tend to separate them.

U-shaped links 19 are pivotally mounted on the press element 10 by a pin 20 with its axis in alignment with the axes of the lug eyes. Between the upper ends of these links 20 I mount a lever 21 on a pin 22, the lever carrying an offset yoke 23 in which a roller 24 is pivotally mounted and adapted to engage the upper press jaw 11. As the lever is forced downwardly to full line position, 25 shown in Fig. 1, the press jaws will be forced together and as they move that portion of the metal forming the outer half of each eye will be swaged and forced inwardly against the mandrels 9 until the eyes are reformed 30 to conform to the mandrels, after which the lug is removed from the press, the taper mandrels are knocked out and the taper eyes left are reamed out, removing just sufficient metal to true up the eye to the correct diameter, after which the lug is ready to be 35 reinstalled in the chain and will render practically as good service as a new lug, because all of the wear in service takes place on the outer half of the lug eyes and the inner half 40 is left unworn. Therefore when the outer half of the eye is reformed the centers of the eye opening are not disturbed and all reformation is confined to that half of the eye which is subjected to wear and deformation 45 in use. This will result in large economies in mining operations and the reforming can be done without skilled labor.

Though I have described with great particularity the details of the embodiment of the invention herein shown, it is not to be construed that I am limited thereto, as changes in arrangement and substitution of equivalents may be made by those skilled in the art without departing from the invention as defined in the appended claims.

What I claim is:—

1. The herein described method for the reformation of worn chain lugs, which consists in removing the worn lug from the chain, 60 heating its eyes, and swaging the worn portions of the deformed lug eyes against mandrels resting against the unworn portions of the lug eyes until the centers of the eyes assume their original distance from each other.
2. The herein described method for the

reformation of worn chain lugs, which consists in removing the worn lug from the chain, heating its eyes, swaging the worn portions of the deformed lug eyes against mandrels resting against the unworn portions of the lug eyes until the centers of the eyes assume their original distance from each other, and reaming out the reformed eyes.

3. An apparatus for reforming chain lugs comprising a press having jaws recessed to receive and conform to the body portion of a new unworn lug in which the eyes are formed, and leverage means to force the jaws against deformed lug eyes to swage the worn portion of the lug eyes until the centers of the eyes assume their original distance from each other, in combination with mandrels seated against the unworn portion of the lug eyes and against which the worn portion of the eyes are adapted to be swaged by the press.

4. An apparatus according to claim 3, in which the mandrels are slightly tapered.

5. An apparatus according to claim 3, in which the press comprises spring separated members, means to guide said members in rectilineal movement, and leverage means comprising links pivoted to one press member and carrying a roller bearing lever engaging the other press member with the axis of the links and of the roller in substantial alignment with the centers of the eyes of the chain lug interposed between the press elements.

6. A press according to claim 3, in which the press jaws engage and brace the back portion of the lug body and eyes.

In testimony whereof I affix my signature.
